UNITED STATES PATENT OFFICE.

AXEL F. HOLMBERG AND MAXIME J. BRIZARD, OF BURLINGAME, CALIFORNIA.

ENGINE-HOOD AND RADIATOR-COVER.

1,176,219.

Specification of Letters Patent. Patented Mar. 21, 1916.

Application filed July 28, 1915. Serial No. 42,317.

To all whom it may concern:

Be it known that we, AXEL F. HOLMBERG and MAXIME J. BRIZARD, citizens of the United States, residing at Burlingame, in the county of San Mateo and State of California, have invented new and useful Improvements in Engine-Hoods and Radiator-Covers, of which the following is a specification.

10 This invention relates to an engine hood and radiator cover.

The object of the present invention is to provide a simple, substantial, cheaply manufactured, easily applied form of engine hood and radiator cover, together with means for securing same in position when applied.

15 The invention consists of the parts and the construction and combination of parts as hereinafter more fully described and 20 claimed, having reference to the accompanying drawings, in which—

Figure 1 is a side elevation of the radiator cover and engine hood. Fig. 2 is a plan view of same. Fig. 3 is a front view. Fig. 25 4 is an enlarged section on line 4—4 of Fig. 2. Fig. 5 is a detail view of the casting.

Referring in detail to the drawings, A indicates in general the engine hood and B the radiator cover; the radiator cover and 30 hood being in this instance particularly constructed for application on "Ford" automobiles. The object is to change the appearance of the radiator and hood and also to 35 simplify the construction and increase the cooling capacity or space between the engine and hood.

The radiator cover proper consists of a continuous rim 2, which is beaded, as at 3, 4 and 5, to produce an ornamental effect, 40 and also for the purpose of reinforcing and strengthening the metal in cross section. The lower ends of the rim are outwardly turned, as at 6, at each side to produce supporting flanges and means for attaching the 45 rim to the frame of the car, indicated at 7; the flanges 6 being perforated, as at 8, to permit the bolt 9 now in use to be passed through the flanges to secure same.

The central upper portion of the rim 2 50 is cut away, as indicated at 10, to permit the radiator cover to be placed in position with relation to the filling spout 11, and the rim is here secured by a plate 12 which serves two functions hereinafter to be described.

55 The plate 12 has a pocket 13 formed on one side which fits the contour of the filling

spout 11, and it is also provided with two threaded openings 14 through which screws are passed to secure the rim of the radiator cover section B to the plate by means of 60 bolts or screws 15. The radiator cover is thus secured at three points; the base section being secured by means of flanges 6 and bolts 9 while the upper central section of the cover is secured in position by surrounding the spout 11 and by the insertion and application of the locking plate 12 and screws 15.

The plate 12 is preferably cast of brass or similar metal, and is provided with an upwardly extending flange 17 in which is formed a groove or pocket 18 which is provided for the purpose of receiving the end of a hinge rod 19 about which each side of the hood A pivots; the other end of the rod 19 being supported by a flange 20 formed on the cowl 21 which forms a permanent part of the machine.

The hood proper is made in four sections 22, 23, 24 and 25; the sections 23 and 24 being secured to the opposite leaves 26 mounted on rod 19, while sections 22 and 25 are secured to hinges 27, which in turn are secured to the lower ends of the cover sections 23 and 24. The lower ends of sections 22 and 25 are in turn secured to the frame of the car by means of spring hooks 28 of the usual construction. The hinges employed are preferably of the piano hinge type. This permits the hinges to be entirely concealed interiorly of the hood and also permits a more rigid substantial construction as the metal cover sections, when secured to same, are folded over the leaves of the hinges and riveted thereto, thus providing several thicknesses of metal at this point which materially stiffens the construction, thereby eliminating any longitudinal flexibility and play which usually occurs when ordinary hinges are employed.

A radiator cover constructed as here shown merely forms a cover for the old radiator now employed, indicated by dotted lines at 29. Being necessarily larger it compels the provision of a larger hood, thus increasing the space between the engine and the hood and consequently permitting a larger volume of air to enter through the louvers, indicated at 30, with a consequent increase in cooling efficiency.

The device is simple and substantial in construction and may be quickly applied or

detached, as it is only necessary to remove the bolts 9 and screws 15 to remove the hood and cover as a whole.

The materials and finish of the several parts of the device are such as the experience and judgment of the manufacturer may dictate.

We wish it understood that various changes in form, proportions and minor details of construction may be resorted to within the scope of the appended claims, and that we do not wish to limit ourselves to the specific design and construction here shown.

Having thus described our invention, what we claim and desire to secure by Letters Patent is—

1. The combination with the radiator and main frame of an automobile, of a cover section adapted to be placed over the radiator, and means for securing said cover section when in position on the radiator, said means including a plate recessed to fit the radiator filling spout, and having bolt holes to receive cover securing screws.

2. The combination with the main frame on an automobile and the radiator and filling spout formed thereon, of a cover section for the radiator having a slot formed therein adapted to straddle the spout, a

locking plate adapted to straddle the spout, means for securing the cover section to the plate, and means for securing the lower ends of the cover section to the frame.

3. The combination with a radiator cover of the character described and an engine hood, of a locking plate adapted to straddle the filling spout on the radiator, means for securing the cover to the plate, a grooved lug formed on the plate, and a central hinge rod on the hood adapted to be supported by the grooved lug on the plate.

4. The combination with the radiator and hood of an automobile, of a radiator cover section and a plate having an upwardly extending recessed portion adapted to receive one end of the hinge rod of the hood, and having a recess at the front to fit around the radiator filling nozzle, and screw openings through which to secure the radiator cover section.

In testimony whereof we have hereunto set our hands in the presence of two subscribing witnesses.

AXEL F. HOLMBERG.
MAXIME J. BRIZARD.
